UNITED STATES PATENT OFFICE.

HANNAH O. PERRY, OF DARIEN CENTER, NEW YORK.

ATTACHMENT FOR KNITTING OR CROCHET NEEDLES.

Application filed July 10, 1923. Serial No. 650,677.

To all whom it may concern:

Be it known that I, HANNAH O. PERRY, a citizen of the United States, residing at Darien Center, in the county of Genesee and State of New York, have invented new and useful Improvements in Attachments for Knitting or Crochet Needles, of which the following is a specification.

This invention relates to a holder for 10 crochet needles and other needles used for an analogous purpose, and the primary object of the invention is to provide a simple attachment which will hold its adjustment by frictional engagement with the body of 15 the needle to keep the hook in proper position for easy and rapid working.

The improved attachment consists of a strip of material of suitable length with 20 openings therethrough at regular intervals through which the needle is passed, the attachment being positively held in its adjusted position as may be desired by the frictional engagement of the walls of the openings with the body of the needle. The 25 attachment is adapted to be applied to a needle body of equal diameter throughout or of any other cross sectional contour and may be used with either single or double pointed needles and can be moved into any 30 position to suit any size of hand. The material used in the formation of the attachment will be such as to stiffen the body portions of long fine needles, and being of a narrow and comparatively long construction, 35 it is not cumbersome and does not retard the work by its use. When it is desired to have the body of the needle clear of any attachment, the improved device may be readily removed.

40 With these and other objects and advantages in view, the invention consists in the construction and arrangement of the attachment which will be more fully hereinafter described and claimed.

45 In the drawing:

Fig. 1 is a perspective view of a double crochet needle, showing the improved attachment applied thereto and the manner of grasping the same;

50 Fig. 2 is a longitudinal vertical section of the improved attachment in the position it occupies when applied to a needle, the latter being partially illustrated in dotted lines;

55 Fig. 3 is a top plan view of the improved

attachment in the position it assumes when applied; and

Fig. 4 is a plan view of the improved attachment in its normal condition.

The improved attachment consists of a 60 comparatively narrow strip 5 of flexible material of any character adapted for the purpose, but practice has demonstrated that leather is preferable. The strip 5 is finished with rounded ends 6 and at regular intervals 65 throughout the length thereof and in the center are a plurality of openings 7 which are in longitudinal alinement.

In applying the improved attachment the hook end of the needle 8 is inserted through 70 the first opening 7 at either end of the strip and successively pushed through the series of openings and the strip drawn up over the body 9 of the needle in the position desired by the user or knitter. To permit the 75 needle to be inserted through the openings, it is necessary that the strip be bent so as to bring the openings in position for penetration, and in bending the strip of material, the walls of the openings are alternately disposed in reverse angles relatively 80 to the needle, as clearly shown by Fig. 2, and it is also required that the strip be bent or shaped in corrugated form so that the corrugated portions 10 will be located at 85 opposite sides of the needle with both extremities 11 on the same side. By thus shaping the strip the walls of the openings 7 will set up a firm frictional grip on the body 9 of the needle 8, owing to the reverse 90 angular positions of the walls of said openings, and as a consequence, the improved attachment will be positively held in its adjusted position and in the shape desired to serve as a gripping guide for the user of 95 the needle in order to maintain the hook 12 in proper position. When the needle having the attachment thereon is grasped by the user, the forefinger and thumb of the hand will occupy the positions shown by Fig. 1, 100 or the finger and thumb may be applied at a point in rear of that shown by Fig. 1, but in all methods of grasping the needle with the improved attachment thereon, the finger and thumb will bear upon opposite 105 portions of the needle in the open spaces between the walls of the corrugations or flutings and the adjacent fingers may touch or lightly bear upon the edge of the strip within the hand, to assist in maintaining 110

the needle and particularly the hook 12 in the position best adapted for effecting crochet and knitting operations. At any time desired the improved attachment may be 5 shifted lengthwise on the body of the needle, or, if it is required to use a needle for carrying a line of stitches, the improved attachment may be readily removed.

As hereinbefore noted, the attachment 10 when applied to a needle and particularly a long fine needle will reinforce the body of the latter, and in all uses of the device the needle is prevented from slipping or rolling in the hand of the user.

15 In view of the simplicity of the improved attachment, it can be easily manufactured and sold at a small cost price, and it will be understood that the general proportions and dimensions thereof may be varied at 20 will to adapt the same for use on needles of different sizes with the same degree of efficiency.

What is claimed as new is:

1. An attachment for knitting and cro- 25 chet needles, consisting of a strip of flexible material with openings therethrough in positions for successive insertion of a needle extremity to effect a removable and frictional engagement with the body of the 30 needle, the strip being caused to assume a regularly corrugated form on the needle body to provide for holding the knitting extremity of the needle in working position.

2. An attachment for knitting and cro- 35 chet needles, consisting of a strip of flexible material with a plurality of regularly spaced openings disposed in longitudinal

alinement for successive engagement with a needle extremity and body when the strip is bent in reverse directions to bring the 40 openings in insertible alinement.

3. An attachment for knitting and cro- 45 chet needles, consisting of a strip of flexible material having openings therein to receive the needle and assuming a corrugated form when applied to the needle to provide alter- 50 nate open and projected portions of the strip at opposite sides of the needle body.

4. An attachment for knitting and cro- 55 chet needles, consisting of an elongated comparatively narrow strip of flexible ma- 60 terial with a plurality of corrugations and spaced openings formed in parts of the corrugations and in longitudinal alinement to receive means for maintaining the cor- 65 rugations in regular form.

5. An attachment for knitting and cro- 70 chet needles, consisting of an elongated comparatively narrow strip of flexible ma- 60 terial having a plurality of openings ex- 75 tending lengthwise thereof and adapted to be disposed in alinement by bending the strip at intervals throughout its length.

6. An attachment for knitting and cro- 75 chet needles, consisting of an elongated comparatively narrow strip of leather of 80 suitable thickness with successive corruga- 85 tions of similar dimensions provided with a plurality of openings disposed in longi- 90 tudinal alinement through opposite por- 95 tions of the corrugations.

In testimony whereof I have hereunto set my hand.

HANNAH O. PERRY.
